UNITED STATES PATENT OFFICE.

ELLWOOD M. SHANNON, OF BALA, PENNSYLVANIA.

MALLET LOCOMOTIVE.

Application filed September 3, 1926. Serial No. 133,393.

My invention relates to certain improvements in locomotives of a simple "mallet" type in which the steam from the superheater is carried to the front and rear cylinders, 5 which are located respectively on the front and rear frames of the locomotive.

The object of my invention is to provide a distributing chamber in which the steam enters from the superheater and from which 10 the steam is distributed to the cylinder on the front and rear trucks.

In the accompanying drawing:

Fig. 1 is a plan view illustrating my improved structure and showing its connection 15 with the pipes leading to the front and rear cylinders.

Fig. 2 is a sectional view on the line 2, 2, Fig. 1, showing a portion of the smoke box in the boiler in dotted lines.

20 Fig. 1 is a steam distributor which is arranged transversely under the smoke box of a locomotive. This distributor has a flange 2 which is bolted or otherwise secured to the casing of the smoke box 3 shown by dotted lines in 25 Fig. 2.

The casing of the smoke box, in the present instance, is cut away to receive the distributor. The distributor has passages 4 in its upper surface which communicate with 30 the transverse chamber 5. The passages 4 are connected to suitable pipes with the superheater of the locomotive.

Depending from the center of the distributor is a projection 6 having a socket 7 for 35 a ball section 8 of a steam pipe 9 which is coupled in like manner to a pipe 10 which leads to the two cylinders on the forward frame of the "mallet" locomotive, so that the steam can freely pass from the chamber 5 through the pipe 9 of the said cylinders. 40 Projecting at each side of the casting 1 is a curved neck 11 having a flange 12 in the present instance. Each flange is secured to a flange 13 on a pipe 14 which leads to one of 45 the cylinders on the rear frame of the locomotive.

In some instances the flange of the distributor may be extended to form the bottom section of the smoke box of the boiler.

By this construction, the steam from the 50 superheater entering the chamber 5 through the passages 4 on each side of the center of the structure will be evenly distributed to the front and rear cylinders of the locomotive. This construction is very simple and the 55 couplings can be readily made and maintained without leakage as the entire construction is carried by the smoke box of the locomotive boiler.

I claim:

1. The combination in a simple "mallet" locomotive, of a smoke box, of a boiler; a distributor secured to the underside of the smoke box and having a steam chamber therein; a passage in the structure arranged 65 to be connected to the boiler, and said structure having passages arranged to communicate with the pipes leading to the cylinders on the forward frame and cylinders on the 70 rear frame of the locomotive.

2. The combination in a simple "mallet" locomotive; of a smoke box; of a boiler; a steam distributor secured to the underside of 75 said smoke box, said distributor having a steam chamber therein and having two openings, one on each side of the center arranged to receive steam from the boiler, and having a central passage communicating with the pipe leading to the cylinders on the forward frame and having end passages arranged to 80 be coupled to the pipes leading to the cylinders on the rear frame of the locomotive.

3. A distributor for a simple "mallet" locomotive having a flange arranged to be secured to the underside of the smoke box of 85 the boiler of a locomotive and having a chamber therein, said distributor having openings in the upper surface at each side of the center arranged to receive steam from the boiler, and having a depending portion arranged to 90 be coupled to a pipe of the front cylinders of the locomotive, and having passages at each end in the form of flanged necks and arranged to be coupled to pipes leading to the rear cylinders of the locomotive.

ELLWOOD M. SHANNON.
